UNITED STATES PATENT OFFICE.

HENRY W. CARR, OF SAN FRANCISCO, CALIFORNIA.

FURNACE.

Application filed August 14, 1925. Serial No. 50,201.

My invention relates to the class of furnaces for the treatment of various materials to secure results according to the nature of the substances treated, as, for example, the recovery, concentration or reduction of values from ores; the roasting, calcining, drying, dehydrating or precipitation where it is desired to obtain a by-product of gases such as CO_2 or other fumes such as quicksilver, zinc and other gaseous products; or the treatment for any purpose of materials requiring furnace heat.

My invention is particularly adapted for and is designed for the treatment of such materials as have a tendency to scale, cake or slag; and it has for one of its objects the provision of a furnace in which simple and effective means are present to prevent the caking of the material upon the furnace walls, and thereby to avoid the necessity of the customary forms of rabbling.

Another object is to subject the material to and advance it over the heated surface in a manner conducive to equability of effect.

Still another object is to provide for a vacuum in the treating chamber. These and other objects will hereinafter become apparent in the course of the following description of a preferred form of my furnace as illustrated in the accompanying drawings; it being understood that various changes may be made in the form, proportions and arrangement of parts without departing from the spirit of my invention as defined by the claims hereunto appended.

My furnace, briefly stated, consists of a heating member in the form of a flue, through which the heating medium is passed; a shell enveloping and spaced from said flue and forming a fluid tight treating chamber thereabout; a revoluble reel within said treating chamber, carrying members adapted to lift and drop the material, to advance it from inlet to discharge, and to scrape and keep clean the outer surface of the heating flue and the inner surface of the shell; and means for effecting and maintaining a vacuum or partial vacuum in said treating chamber.

Referring to the accompanying drawings, Fig. 1 is a vertical, longitudinal section of my furnace.

Fig. 2 is a section on the line 2-2 of Fig. 1.

1 is the heating flue in the form of a metallic tube, having communication at one

end with the source of heat, such as the fire box 2, and communicating at its other end with the smoke stack 3.

The heating flue or tube 1, in its best arrangement is journaled at its end connections in bearings indicated at 4, adapting it for rotation on its axis; and for this purpose it is provided with a gear 5 meshing with a pinion 6 on a drive shaft 7.

Enveloping the heating flue 1 and spaced from it is a metallic shell 8, the space between the shell and flue being the treating chamber, indicated by 9. The connection between the shell and flue as indicated by 10 is such that the treating chamber 9 is fluid tight, in order to establish and maintain therein a vacuum or partial vacuum, for which purpose there is a connection 11 to a vacuum pump 12.

Also, for preserving said vacuum, the feed spout 13 to said chamber is fitted with a fluid tight valve 14, and the discharge pipe 15 is fitted with a similar fluid tight valve 16.

Within the heating chamber and extending between the feed and discharge thereof is a revoluble reel of which 17 indicates its two heads. These heads are fitted with gears 18 meshing with pinions 19 on the drive shaft 7, whereby the reel is rotated about the heating flue 1 as an axis. Between the reel heads 17 and carried by the outer portions thereof extend, preferably at an angle to the reel axis, as indicated in Fig. 2, in order to secure an advancing effect, an annular series of lifting and outer scraping rails 20. The inner edges of these rails are bent or flanged at 20', to serve as lifters, and their outer edges lie in close relation to the inner surface of the shell 8 to scrape the material from said surface and prevent caking.

Carried by the inner portions of the reel heads 17 and preferably inclined at an angle to the reel axis, as indicated in Fig. 2, is an annular series of scraper rails 21, the inner edges of which lie close to the outer surface of the heating flue 1 and serve to scrape the material therefrom and prevent caking.

In operation the material fed in at 13 is lifted and then dropped upon the heating flue by the rails 20, and is advanced by said rails and by the rails 21, to the discharge 15. It is thus kept well distributed, and due to this and to the rotation of the heating flue, a maximum equability of heat effect is

secured. Also by the action of the rails 20 and 21, the material is kept well scraped off from all walls of the treating chamber. The fluid tight relation of the several parts permits the application of a vacuum effect to the heating chamber in case, by reason of the nature of the material or of the results sought, such effect is indicated.

I claim:

- 10 1. A furnace comprising a heating flue; means for passing a heating medium through said flue; a shell enveloping, spaced from, and forming a treating chamber around said heating flue; and a 15 rotatable reel of rails within and extending the length of said chamber, said rails being positioned and operating with relation to the inner surface of the shell and the outer surface of the heating flue to 20 scrape said surfaces free of the material.
- 25 2. A furnace comprising a heating flue; means for rotating said flue upon its axis; means for passing a heating medium through said flue; a shell enveloping, spaced from, and forming a treating 30 chamber around said heating flue; and a reel of rails within and extending the length of said chamber, and independently 35 rotatable about the flue, said rails being positioned and operating with relation to the inner surface of the shell and the outer 40 surface of the heating flue to scrape said surfaces free of the material.
- 45 3. A furnace comprising a heating flue; means for passing a heating medium through said flue; a shell enveloping, spaced from, and forming a treating chamber around said heating flue; means for feeding material to one end of said 50 chamber; means for discharging it from the other end; and a rotatable reel of rails within and extending the length of said chamber, said rails being disposed at an angle to the reel axis and positioned and 55 operating to advance the material through the chamber and to scrape said material from the inner surface of the shell and the outer 60 surface of the heating flue.
- 65 4. A furnace comprising a heating flue; means for rotating said flue upon its axis; means for passing a heating medium through said flue; a shell enveloping, spaced from, and forming a treating chamber around said heating flue; means for feeding material to one end of said 70 chamber; means for discharging it from the other end; and a reel of rails within and extending the length of said chamber and independently 75 rotatable about the flue, said rails being disposed at an angle to the reel axis and positioned and operating to advance the material through the chamber and to scrape said material from the inner 80 surface of the shell and the outer surface of the heating flue.

5. A furnace comprising a heating flue; means for passing a heating medium through said flue; a shell enveloping, spaced from, and forming a treating chamber around said heating flue; a rotatable reel within and extending the length of said chamber said reel carrying an inner 85 annular series of rails the inner edges of which are adapted to scrape material from the outer surface of the heating flue, and also carrying an outer annular series of rails, the inner edges of which are flanged to lift and drop the material, the outer edges of said rails being adapted to 90 scrape material from the inner surface of the shell.

6. A furnace comprising a heating flue; means for rotating said flue upon its axis; means for passing a heating medium through said flue; a shell enveloping, spaced from, and forming a treating chamber around said heating flue; and an independently rotatable reel within and extending the length of said chamber said reel carrying an inner annular series of 95 rails the inner edges of which are adapted to scrape material from the outer surface of the heating flue, and also carrying an outer annular series of rails, the inner edges of which are flanged to lift and drop the 100 material, the outer edges of said rails being adapted to scrape material from the inner surface of the shell.

7. A furnace comprising a heating flue; means for passing a heating medium through said flue; a shell enveloping and spaced from said flue with fluid tight connections forming a closed treating chamber around the flue; means for effecting and maintaining a vacuum in said chamber; and a rotatable reel of rails within and extending the length of said chamber, said rails being positioned and operating with relation to the inner surface of the shell and the outer surface of the heating flue to 110 scrape said surfaces free of the material.

8. A furnace comprising a heating flue; means for rotating said flue upon its axis; means for passing a heating medium through said flue; a shell enveloping and spaced from said flue with fluid tight connections forming a closed treating chamber around the flue; means for effecting and maintaining a vacuum in said chamber; and a reel of rails within and extending the length of said chamber, and independently 115 rotatable about the flue, said rails being positioned and operating with relation to the inner surface of the shell and the outer surface of the heating flue to scrape said surfaces free of the material.

In testimony whereof I have signed my name to this specification.

HENRY W. CARR.
